UNITED STATES PATENT OFFICE

HARRY SPIRO, OF CHICAGO, ILLINOIS

CASTING MACHINE

Application filed November 2, 1927. Serial No. 230,558.

This invention relates to improvements in casting machines, and more especially a dental casting machine adapted for casting teeth, plates, bridges, fillings, inlays, inserts, and the like.

Among the features of my invention is the provision of a machine adapted to use flasks of different sizes, with means for centering such flasks under the head of the machine.

10 I also have to provide a ball air joint between the compression head of the machine and the top of the flask so that the head fits tightly on the top of the flask even though the same is not exactly level.

15 In my improved flask I also provide a lead through the plaster or investment both above and below the mould cavity so that the wax may be more easily eliminated therefrom. In flasks as heretofore made there has been a 20 outlet at only one end for the escape of the wax. The wax is ordinarily removed from the investment by immersing the same in boiling water. With only one such outlet it was necessary to boil the investment for a 25 considerable length of time, and then frequently much of the residue of the wax remained. This continued boiling of the investment, which ordinarily is porous and not very strong, resulted in the disintegration of 30 the binder on the surface of the plaster exposed to the action of such prolonged boiling, thus weakening delicate structures within the mould, resulting in rough, irritating, and poor fitting castings, and necessitating much 35 waste of gold in polishing. By the use of my invention, in providing two outlets, the wax ordinarily may be boiled out in from one to two minutes.

Another feature of my invention is the provision of an air outlet through the bottom of the investment thus permitting the air to escape more readily from the mould cavity as the metal enters. This is a great improvement over those devices in which the air must 45 escape through the pores of the investment or plaster. In these older devices, after the wax was removed from the mould cavity, the plaster had to be heated to a high degree to attain the requisite porosity. This heating 50 of the plaster dried it out and frequently ren-

dered it sandy and weak, thus impairing the castings made. In the use of my invention, with an air outlet at the bottom, it is only necessary to dry the plaster at an even, low temperature. It is not necessary to heat it to dry 55 it out and make it porous.

Another feature of my invention is the making of the outer ring of the flask split or hinged thus permitting the easy arrangement of the pattern within the flask before 60 pouring the plaster, and also permitting the easy removal of the plaster and casting after the casting operation.

Another feature of my invention is the provision of an improved sprue former, with a 65 tapering thread at the end, fastened into the base of the plaster model, upon which the wax pattern is formed. This has the advantage of uniting the sprue former solidly to the case and eliminates the danger of it falling off in 70 handling or when the plaster is poured over it. Another feature of the invention is the provision of an adjustable mounting for the sprue former, thus permitting its adjustment to the desired height in the flask. This also permits the removal of the plaster model and 75 wax pattern with the sprue former attached for the purpose of carefully covering the pattern with a coating of the plaster, or "painting" the same, after which when put back 80 into the flask it necessarily assumes its original position. This saves time so that the remainder of the plaster may be poured into the flask before it becomes too thick.

Other features and advantages of my invention will appear more fully as I proceed with my specification.

In that form of device embodying the features of my invention shown in the accompanying drawings, Figure 1 is a view in side elevation, Figs. 2, 3, and 4 are vertical sectional views showing the compression head in different positions, Fig. 5 is an enlarged vertical sectional view showing the air outlet at 90 the bottom of the flask, Fig. 6 is a view taken as indicated by the line 6 of Fig. 7, Fig. 7 is an enlarged view of a portion of the compression head, Fig. 8 is a view taken as indicated by the line 8 of Fig. 1, Fig. 9 is a view taken 95 as indicated by the line 9 of Fig. 1, Fig. 10 100

is a view taken as indicated by the line 10 of Fig. 1, Fig. 11 is a view taken as indicated by the line 11 of Fig. 1, Fig. 12 is a view taken as indicated by the line 12 of Fig. 10, Fig. 13 is a vertical sectional view taken through one of the burner pipes, Fig. 14 is a vertical sectional view showing the rack and pinion adjustment for the work table, Figs. 15, 16, and 17 are vertical sectional views taken through the flask, Fig. 18 is a top plan view of the flask, and Fig. 19 is a view in side elevation of the flask showing a portion of the outer ring hinged.

As shown in the drawings, the machine comprises a suitable base 10 with an upright 11 having its upper end bent over as indicated by 11^a and formed into a substantially cylindrical tubular guide 12 for the reciprocable compression head 13.

20 The compression head 13 is carried on the lower end of a shaft 14 and mounted thereon by means of the ball joint 15 so that the head will make an airtight seal on the top of a flask even though its upper surface be not entirely level. Inside the head is preferably provided an asbestos gasket or washer 13^a to assist in making a tight air seal with the top of a flask. The shaft 14 is reciprocably mounted in the lower end of a sleeve 16 which is provided with rack teeth 16^a engaged by the teeth of a gear 17 on a shaft 18 controlled by an operating handle 19 so that movement of the handle 19 will operate to raise or lower the sleeve 16 carrying the compression head 13.

25 The upper end of the sleeve 16 has a sliding airtight fit over a hollow shaft 20. 21 indicates a suitable air pipe for supplying air to the port 20^a in the shaft 20 which air is supplied to the port 14^a in the shaft 14 carrying the compression head 13.

As stated before, the shaft 14 is reciprocably mounted in the lower end of the tubular member 16, and above its upper end the air passage through this member 16 is closed by a valve 22 except when the member 14 is slid upwardly, so that its upper end 14^b engages the lower end 22^a of the valve 22 to lift the same and open such air passage. The member 14 is normally held in its lower position by means of the spiral spring 23 and its sliding movement in the tubular member 16 is limited by means of the pin 24 having its end operating in the groove 25.

30 When the compression head is lowered, the air is shut off by the valve 22, until the head engages the upper edge of the flask when the shaft 14 is raised relatively to the valve 22 against the compression of the spring 23 until the valve is opened. As soon as the valve is opened, air is permitted to pass through into the flask as shown in Fig. 4.

35 26 indicates an adjustable flask supporting table or work support mounted in a standard 27 on the base 10. The support 26 is carried

by a shaft 28 provided with rack teeth 29 engaged by a pinion 30 mounted on a shaft 31 controlled by a hand wheel 32. By these means the work table may be raised or lowered to any desired height to accommodate the same to the particular flask being used. The table is adapted to be held in any desired position by means of the dog 33 adapted to be set between the teeth 34 on the member 28.

I have also provided improved centering means on the table 26 operating in conjunction with flasks of different sizes to automatically center the same under the compression head 13. Such means comprise radial grooves or slots 35 set at ninety degrees in the table 26 and co-operating legs or lugs 36 on the bottoms of the flasks 37 to cause them to automatically center themselves on the table.

35 My improved flask 37 is of the general type shown in my Patent 1,639,416 dated August 16, 1927, the upper edge of the cylindrical wall being bent inwardly and downwardly as indicated at 38, with its inner edge bent downwardly to form the inner depending concentric ring 39 lying inside of and parallel with the outer wall of the flask. This ring 39 prevents the escape of pressure from the top of the flask between the investment and the outer wall of the flask as described in the patent referred to.

40 In the use of the machine, the flask 37 is inverted as shown in Fig. 15 on top of a suitable support 40 which carries an adjustable mounting for the sprue former 41. Such adjustable mounting comprises two clamps or springs 42 on the part 43 so that the sprue former may be slid upwardly or downwardly but is firmly held at any desired height. The end of the sprue former 41 has a tapered thread 44 adapted to be screwed into the base of the plaster model 45 upon which the wax pattern 46 is formed. 47 indicates a wax lead from the model to the sprue former, and 48 a wax lead from the model to the bottom (when the flask is upright as in the casting process) of the flask. The part 43 is separable from the flask support 40.

45 After the parts are in position, as shown in Fig. 15, the bottom plate 49 of the flask is put in place and the investment or plaster 50 poured in. The flask is then turned in the upright position, as shown in Fig. 17, the support 40 removed, the sprue former 41 taken out, and the wax melted out by drying the mold at an even, low temperature.

50 It is to be noted that one side or portion of the flask 37 is hingedly attached, as indicated by 37^a (see Figs. 18 and 19), thus permitting easy arrangement of the pattern within the flask before pouring the plaster and easy removal of the plaster and casting after the casting operation. It is also to be noted that I provide the inner ring 39 in the flask which is hugged by the investment in shrinking to make an air-tight joint. In providing an air-

tight joint at this point, it is not necessary to have an air-tight joint between the outer wall 37 and the investment 50. In fact, I provide the inner ring 39 to make the air seal to prevent leakage of air between the investment 50 and the outer wall 37. Since the air seal is made around the ring 39, the outer wall 37 does not have to have an air-tight connection with the outer surface of the investment 50. 5 Because of this construction, I can make a portion of the outer wall 37 removable, here shown as 37^a, which is hingedly attached.

10 The center of the table 26 is provided with an air outlet 51 carrying within the same a screen 52 mounted on a spring 53 and above the screen 52 there is preferably mounted a porous disk 53^a, made of paper, cloth, or the like adapted to be engaged by the outlet flange 54 on the bottom of the flask so as to make 15 an airtight joint against the compression of the spring 53.

20 55 indicates a blow torch adapted to be used for melting the metal 56 in the flask just before the application of air pressure. The compression head carries an arm 57 adapted to engage this blow torch and move it out of the way as the head is lowered. The swinging of the blow torch automatically shuts off the air and gas. The air and gas pipes of the 25 blow torch, as indicated by 55^b and 55^a, are rotatably mounted in the ends of the supply pipes 57^a and 57^b (see Figs. 10 and 12), so that as the blow pipe is swung out of position the air and gas are automatically shut off. 30 35 The swinging of these pipes closes the ports 58 and 59. 60 indicates a by-pass so that a small amount of gas will continue to flow through the blow torch for maintaining a pilot light.

40 61, 61 indicate burners mounted on the bed 26 for keeping the flask heated. The gas supply to these burners is controlled by shut-off valve 62 with a handle 62^a. The gas supply to the burners 61 is adapted to be shut-off automatically when the blow torch is 45 swung to one side. This is accomplished by forming a latch 63 on the end of the valve handle 62^a, said latch adapted to be engaged by the dog 63^a on the blow torch, so that 50 when the blow torch is swung to one side the dog 63^a will engage the latch 63 to turn the valve handle 62^a to shut-off the gas to the burners 61. The gas burners may be turned on again by depressing the latch 63 to clear 55 the dog 63^a.

56 Means are also provided for holding the compression head in its lowered position. Such means comprise tracks 64 in the sides of the guide 12 and pins 65 carried on the ends 60 of a yoke 66 having its lower end rotatably mounted on the member 14 (see Figs. 6 and 7). In lowering the head, the pins travel through the inclined groove 64^a until the springs 67 throw them across to strike the shoulders 68. 65 Upon release, the pins will then be forced up

70 into the notches 69^a. Upon again lowering the head, the pins will clear the shoulder 68 and be free to travel upwardly through the groove 69, thus permitting the head to be raised.

75 While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

80 What I claim is new, and desire to secure by Letters Patent, is:

85 1. In a device of the character described; a flask supporting table; an adjustable compression head arranged above the table and centered with respect thereto; a flask for use on said table; and co-operating means on the flask and table for automatically centering the same under the compression head, said means comprising co-operating radial slots 90 and projections adapted to engage said slots.

95 2. In a device of the character described; a flask supporting table; an air outlet in said table having a porous member therein spring-pressed upwardly; a flask; investment in the flask; a mould cavity in the investment; an outlet flange in the bottom of the flask, adapted to engage with the porous member in the outlet in the flask supporting table when the flask is in position; and an air outlet communicating from the mould cavity through the outlet flange in the bottom of the flask to the porous member in the air outlet in the flask supporting table.

100 105 3. In combination with a casting machine; a flask; means on the machine for supporting the flask; investment in the flask; a mold cavity in the investment; a sprue opening in the investment to the mold cavity; an air outlet in the investment leading from the mold cavity; a porous member; and means on the casting machine for holding the porous member over the end of the air outlet when the flask is supported on the machine.

110 115 4. In a device of the character described a flask-supporting table; a compression head arranged above the table; a spring-pressed cap at the lower edge of the head adapted to seat on a flask on the table as the head is lowered; locking mechanism adapted to lock the head in lowered position as the head is lowered the first time against the tension of the spring means carrying said cap; and means adapted to release said locking mechanism when the head is lowered a second time.

120 125 In witness whereof, I have hereunto set my hand this 18th day of October, 1927.
